G. E. PICKUP

ROCK OVER MOLDING MACHINE

Filed March 9, 1922.

FIG. 1

Fig. 3

UNITED STATES PATENT OFFICE.

GEORGE E. PICKUP, OF NEWARK, OHIO, ASSIGNOR TO THE WEHRLE COMPANY,
OF NEWARK, OHIO, A CORPORATION OF OHIO.

ROCK-OVER MOLDING MACHINE.

Application filed March 9, 1922. Serial No. 542,363

To all whom it may concern:

Be it known that I, GEORGE E. PICKUP, a citizen of the United States, residing at Newark, in the county of Licking and State of Ohio, have invented certain new and useful Improvements in Rock-Over Molding Machines, of which the following is a specification.

The invention relates to molding machines of the rock-over table type, and more especially to machines of this class which are operated by hand power.

The aim of the invention is to produce such a machine which is capable of operation with the utmost ease and facility, and hence is particularly adapted for use in making molds relatively larger than is practicable with hand power machines now upon the market.

With this aim in view, the principal object of the invention specifically stated, is to provide a novel means for supporting the work table, which enables the operator to swing it with a minimum expenditure of effort from a rearward horizontal position at a convenient height from the floor, to a forward inverted position elevated so as to provide ample space between it and the floor for the efficient and unrestricted operation of the pattern-stripping device.

A further and ancillary object of the invention is to increase the effectiveness of the counterbalancing means for the table.

Herein, a single embodiment only of the invention is illustrated and described, but it will be understood that the invention is not limited to any precise construction and arrangement of the parts, for many changes therein may doubtless be made by those skilled in the art but without departing from the spirit and scope of the invention as expressed in the appended claims.

In the drawings, Figure 1 is a side elevation of my improved machine showing the turn-table in its rear or operative position. Fig. 2 is a vertical central sectional view through the machine and showing the table in its forward inverted position, the intermediate position being shown in broken lines.

Fig. 3 is a fragmentary sectional view showing a detail of construction. 50

The machine comprises a frame 7 formed from two side members 8 connected at their lower forward ends by a cross frame member or bracket 9 and at their rear ends by upper 55 and lower rods 10 and 11. The latter is extended at its opposite ends to provide journals for the rear supporting wheels 12.

The forward cross piece 9 is cast to provide centrally thereof a suitable support for 60 a pivot rod 13 upon which a forward central supporting wheel 14 is journaled.

Upon opposite sides of the front piece 9 are forwardly projecting portions 9^a carrying upright tubular stems 15 in which are 65 guided for vertical movement a pair of horizontal universally mounted bars 16 forming mold rests, one at each side of the machine. These bars are pivoted at their centers to supporting members 17 so as to have a limited 70 rocking movement on their axes 18. To this end the parts are provided with coacting stops 19 and 20. The members 17 are mounted upon screw-threaded rods 21 in the opposite ends of a cross bracket 22 having bearings 23 for this purpose. The bracket 22 in turn is pivotally supported centrally thereof as at 24, to a cross bar 25, having formed integral therewith at each end two tubular 75 members or sleeves 26 slidable upon the stems 15. In Fig. 3 the left end of the bracket 22 is broken away to expose one of the sleeves 26 on the bar 25. Said sleeves 26 are preferably closed at their upper ends so as to 80 form inverted cup members, and carry centrally depending guide rods 27 which are arranged to operate within the tubular stems 15.

The supporting bars 16, constituting the mold rest, are lowered to strip the mold 85 from the pattern by means of a U-shaped rod 29 forming at its forward end a foot lever and pivotally connected with the members 26 through the medium of a pair of bars 30 mounted upon a cross rod 31. The 90 connection between the bars 30 and the members 26 may comprise suitable plates 32 and bolts 33. Rigid with the bars 30 is

an arm 34 arranged approximately at right angles thereto and connected at its free end, by means of a spring 35, to the cross rod 11. It will be observed that this spring 35 tends to move the mold rest bars 16 upwardly so as to provide yielding supports for the mold. When the latter has been placed upon this support and the pattern "rapped", the mold is stripped from 10 the pattern (the latter being carried by the table in the well known manner) by a depression of the lever 29.

It will be obvious that in some instances a substantial amount of movement in a 15 vertical direction must be imparted to the mold in order to strip it from the pattern. It therefore is desirable that the rock-over table when in its inverted position, as shown in Fig. 2, be elevated to provide ample 20 space between it and the normal position of the mold rest.

The rock-over work table is indicated generally at 36. This table is mounted in a 25 frame for swinging movement from a rearward horizontal position (Fig. 1) to a forward inverted position (Fig. 2). Preferably it is cast in the form of a rectangular frame having at its free edge a pair of handles 36^a to facilitate its swinging operation.

The means for supporting the work table is especially constructed and arranged so as to enable the operator to move the same from a rearward normal position to a forward elevated and inverted position with the utmost ease. This means in the present 35 instance comprises a pivotal support or carrier in the form of a pair of arms or members 37 (Fig. 2) pivoted at 38 in the 40 frame between the side members 8 thereof and near its forward upper edge portion. The table is pivoted to the members 37 as at 39 upon an axis normally spaced a 45 substantial distance rearwardly from the fixed axis upon which the members are supported.

Normally the members 37 are supported against downward swinging movement in the frame by means of stop lugs 40 formed 50 upon the outer sides of the members 37 and adapted to engage with lugs 40^a upon the upper inner side edges of the side members 8 of the frame. The members 37 occupy such normal horizontal position while 55 the table is swung from its rearward position approximately into an upright position when relative movement between the table and the members 37 is limited to accomplish the shifting of the pivotal axis 60 upon which the table turns from the axis 39 to the axis 38. Such limitation of the movement of the table relative to the members 37 is accomplished in the present instance by rearwardly extending arms 41 65 rigid with the table and adapted to en-

gage with stop lugs 41^a upon the inner sides of the members 37 opposite the stop lugs 40. When the arms 41 thus engage the stop lugs 41^a the members 37 swing upon their pivotal axis 38 into an upright position 70 while the table moves forwardly and downwardly from an upright position into an inverted elevated position. To limit such downward movement of the table, the members 37 have rigid therewith arms 42 75 extending in the normal horizontal position of the members downwardly from the axis 38 and these arms 42 are adapted to engage with stop lugs 42^a upon the inner sides of the frame member 8 when the members 37 reach an upright position and the 80 table its forward horizontal position.

For the purpose of counterbalancing the weight of the table 36 acting upon the members 37, as the table approaches either 85 extreme limit of its movement, I provide one or more contractile springs 43 connected with the arms 42 of the members 37 and with a cross rod 44 in the lower portion of the frame. Preferably said arms 42 extend slightly forwardly and the arrangement of the springs is such that they exert a slight lifting effect upon the table when 90 in its rearward position.

To assist the operation of swinging the 95 table from its normal rearward position into an upright position, I provide a pair of contractile springs 45 connected with the arms 41 of the table and with the free ends of a pair of arms 46 which are formed 100 integral with the members 37 and in the normal position thereof extend downwardly and rearwardly at an angle of approximately 45 degrees. These arms 46, it will be observed from Fig. 2, swing upwardly 105 as the table moves forwardly and downwardly. Hence their weight tends to assist the springs 43 in counterbalancing the weight of the table in its forward swinging movement.

It will be observed that the table swings through an arc of approximately 90 degrees only relative to the members 37: and that the members 37 swing through an arc of approximately 90 degrees only with respect 110 to the frame. By this arrangement it will be apparent that the amount of expansion of the springs 43 and 45 is relatively slight as compared to the common construction in which the arc of travel for the moving end 115 of the spring is 180 degrees.

The table frame 36 when in its rearward or operative position rests upon the frame 7 (Fig. 1), suitable coacting lugs 48 and 49 on the table and frame respectively being provided for this purpose. To insure 120 that the table will be held in this position so long as may be desired, against the action of the counterbalancing springs 43 and 45, I provide a hook 51 pivoted at 125 52 upon 130

one of the lugs 49 and adapted to engage with a pin 53 carried by the lug 48.

In the operation of rocking the table from its rearward horizontal position to its forward inverted position, it is first swung upwardly upon its axis 39 into approximately an upright position as shown in broken lines in Fig. 2. In this operation the rearward extensions 46 of the members 37 remain stationary until the arms 41 of the table frame engage with the stop lugs 41^a upon the members 37, whereupon the axis of pivotal movement of the table shifts forwardly from the axis 39 to the axis 38. In the following operation the members 37 swing upwardly and forwardly until their swinging movement is stopped by the engagement of the arms 42 with the lugs 42^a. Obviously in such forward movement of the table frame 36 the weight of the rearwardly extending arms 42 of the members 37 tends to counterbalance the downward and forward movement of the table, and the counterbalancing effect is augmented by the springs 43.

It may be observed that in this operation, as the axis upon which the table is swinging shifts from the journal 39 to the journal 38, said axis moves with reference to the weight upon the table so as to follow in the direction of the center of gravity. Consequently, it is possible with my improved machine to turn over the molds of such size and weight as is impossible of accomplishment with machines previously constructed. At the same time, by reason of the ease with which the operation may be accomplished, a considerable saving in time as well as in the effort required is effected.

The pattern may be secured to the table frame in any suitable and well known way. Thus it may be rigid with an auxiliary frame 54 (Fig. 1) secured to the table by means of bolts 55 entered through apertured bosses 56 upon the underside of the table frame. The mold flasks are in turn secured upon the frame 54 and to the table 36 in any suitable way, not herein shown, since it forms no part of the present invention.

I claim as my invention:

1. A molding machine having a supporting frame, a pair of carrier members pivoted to said frame, a table pivoted to said members, means for limiting the extent of relative pivotal movement between the members and the frame on the one hand and the table and the members on the other hand, and spring means tending to assist the upward movement of the table and to resist the downward movement thereof.

2. A rock-over table molding machine comprising, in combination, a supporting frame, a table, means pivotally mounting

the table upon said frame for rocking movement comprising a member pivotally connecting the table and the frame, said table being swingable on said member from a rearward horizontal position to an upright 70 position and having a limited movement with respect to the member whereby as it swings forwardly from such upright position to an inverted position, the pivotal axis shifts from the member to the frame, and 75 spring means tending to resist the downward movement of the table.

3. A molding machine having a rock-over table, and means for pivotally supporting the table comprising a pair of pivoted members upon which said table is mounted for swinging movement, said members having rearward extensions, and springs connecting such rearward extensions with the table to assist the swinging movement of the 80 table from a normal rearward and horizontal position to an intermediate upright 85 position.

4. A molding machine having a rock-over table, and means for pivotally supporting the table comprising a pair of pivoted members upon which said table is mounted for swinging movement, said members having rearward extensions, springs connecting such rearward extensions with the table to assist the swinging movement of the 90 table from a normal rearward and horizontal position to an intermediate upright 95 position, and springs connected with said members to resist the swinging movement of the 100 table into a forward inverted position.

5. A molding machine having a rock-over work table, a pair of members mounted upon a fixed pivot and pivotally supporting said table so that it is swingable from normal operative position through approximately 180 degrees to an inverted pattern-stripping position, the arrangement being such that during a portion of its movement the table swings upon its pivotal connection with the members and during the remainder of the movement swings with the members upon the pivotal axis of the latter.

6. A molding machine having a rock-over work table, a member mounted upon a fixed pivot and pivotally supporting said table so that it is swingable from a normal operative position through approximately 180 degrees to an inverted pattern-stripping 115 position, the arrangement being such that during a portion of its movement the table swings upon its pivotal connection with said member and during the remainder of the movement swings with the member upon the pivotal axis of the latter, and means carried by said member for counterbalancing the weight of the table as it swings from its upright position to its inverted position.

7. A molding machine having a rock-over work table, a carrier member mounted 120

- upon a fixed pivot and pivotally supporting said table so that it is swingable from a normal operative position through approximately 180 degrees to an inverted pattern-stripping position, the arrangement being such that during a portion of its movement the table swings upon its pivotal connection with the member and during the remainder of the movement swings with the member upon the pivotal axis of the latter, and spring means acting between said member and said table so as to counterbalance the latter as it swings from its upright position to its inverted position.
8. A molding machine comprising, in combination, a mold rest, a work table swingable from a rearward substantially horizontal position to a forward elevated but inverted position so as to position a mold carried thereby onto said mold rest, the means for supporting the table comprising a carrier member normally disposed in a substantially horizontal position and in the forward inverted position of the table occupying approximately an upright position.
9. A molding machine comprising, in combination, a mold rest, a work table swingable from a rearward substantially horizontal position to a forward elevated but inverted position so as to position a mold carried thereby onto said mold rest, the means for supporting the table comprising a carrier member normally disposed in a substantially horizontal position and in the forward inverted position of the table occupying approximately an upright position, said table being pivoted to said member and having arms rigid therewith and extending beyond the pivotal connection of the table with the member, and springs connecting said table arms with said member whereby to facilitate the operation of moving the table from its rearward horizontal position to its upright position.
10. In a molding machine, a table, means for supporting the table including a member pivoted on a fixed axis and having an arm extending in the normal position of the parts rearwardly from said fixed axis and an arm depending from said axis, said member being swingable through an arc of approximately 90 degrees, and a spring connected with the depending arm and tending in the normal position of the parts to counterbalance the weight of the table and in the swinging movement of the table from an upright position to a forward inverted position to resist the action of gravity.
11. In a molding machine, the combination of a table and a pivotal support for the table swingable with the table through an arc of approximately 90 degrees only, and a spring having a connection with said support such as to resist its movements toward either extreme position.

12. In a hand power rock-over table molding machine, the combination of a frame, a table and a pivotal support for the table in the frame, said support being swingable through an arc of approximately 70 degrees only, and a spring acting between the frame and said support tending to counterbalance the movement of the table toward one extreme position.

13. In a hand power rock-over table molding machine, the combination of a frame, a table, and a pivotal support for the table in the frame, said support being swingable through an arc of approximately 90 degrees only, a spring acting between the frame and said support tending to counterbalance the movement of the table toward one extreme position, said table being pivoted to said support, and a spring acting between the support and the table tending to assist the movement of the latter from a rearward horizontal position to an upright position.

14. In a molding machine, the combination of a frame, a work table, a pivotal support for the table and the frame comprising a member pivoted upon a fixed axis in the frame and providing a pivotal support for the table, said member having a part adapted to engage with the frame to limit its rearward and downward movement in the frame and a second part adapted to engage with the frame to limit the upward and forward movement of the member relative to the frame.

15. A molding machine having a frame, 100 a pair of members pivoted forwardly in the frame and extending normally in a rearward direction, a table pivoted to said members at a point spaced rearwardly from their connection with the frame, and coacting stop lugs on the members and frame serving to limit the extent of relative swinging movement between these parts.

16. A molding machine having a rock-over work table having means for securing the pattern thereto and pivotally mounted for swinging movement initially on an axis near one edge thereof and finally on an axis spaced forwardly in the direction of movement of the table whereby to carry the mold from a normal rearward position to a forward inverted position.

17. A molding machine having a supporting frame comprising a pair of spaced side members, and a work table pivotally supported between said side members near the upper forward ends thereof and swingable first from a rearward horizontal position in which it supports the mold while being made, and then into a forward inverted position in which the pattern is withdrawn, the arrangement being such that the initial portion of the swinging movement takes place on an axis near the forward edge of 130

the table, and the final portion of the swinging movement takes place on an axis spaced forwardly from the first mentioned axis in the direction of the swinging movement.

5 18. A molding machine having a frame, a pattern-carrying table upon which the mold is made, and means for supporting the table in a normal rearward position for movement to a forward inverted position 10 elevated with respect to the first position, said means including a member pivoted upon said frame, said table being pivoted to said member at a point spaced rearwardly from the first mentioned pivot, and said member in the inverted position of the table occupying an upright position.

15 19. A molding machine having a rock-over work table pivotally mounted for swinging movement initially on an axis 20 near one edge thereof and finally on an axis spaced forwardly in the direction of movement of the table whereby to carry the mold from a normal rearward position to a forward inverted position, and spring means 25 for governing said movement of the table.

20 20. A molding machine having a supporting frame and a work table pivotally supported upon said frame and swingable first from a rearward horizontal position in which 30 it supports the mold while being made and then into a forward inverted position in which the pattern is withdrawn, the arrangement being such that the initial portion of the swinging movement takes place 35 on an axis near the forward edge of the table and the final portion of the swinging movement takes place on an axis spaced forwardly from the first mentioned axis in the direction of the swinging movement.

40 21. A molding machine having, in combination, a frame, a table, means pivotally supporting the table upon the frame whereby the table in swinging from one operative position to another turns successively 45 on two spaced parallel axes, and separate means for controlling the movement on the respective axes.

50 22. A molding machine having, in combination, a frame, a table, means pivotally supporting the table upon the frame whereby the table in swinging from one operative position to another turns successively 55 on two spaced parallel axes, and spring means for controlling such swinging movement of the table.

55 23. In a molding machine, the combination of a main supporting structure, a table, a support movably mounted upon said supporting structure and providing in turn a pivotal mounting for the table, spring means acting between the supporting structure and said support whereby to govern the movements of the latter, and spring means acting between the table and the sup-

port whereby to govern the movements of 65 the table relative to the support.

24. In a molding machine, the combination of a main supporting structure, a table, a support movably mounted upon said supporting structure and providing in turn a 70 pivotal mounting for the table, means tending to move the table in one direction relative to said support, and means tending to resist the movement of the table together with the support. 75

25. A molding machine having, in combination, a main supporting structure, a table, means for supporting the table upon the supporting structure for movement from a normal rearward position into a forward 80 inverted position and vice versa, spring means tending to move the table from its rearward position to an intermediate position, and additional spring means tending to resist movement of the table into its 85 forward inverted position, the first mentioned spring means acting between the table and its support and the last mentioned spring means acting between the supporting structure and the table-supporting means. 90

26. A molding machine having, in combination, a main supporting structure, a work table, means for pivotally supporting the work table upon the supporting structure whereby in the movement of the table from one operative position to another it swings first on one axis and then on another axis, spring means tending to resist movement of the table toward either of said 95 operative positions, and means for locking the table in one of said operative positions. 100

27. A molding machine having a work table swingable on one axis from one operative position into an intermediate position and upon a second axis from said intermediate position into another operative position, and spring means tending to facilitate the movement of the table into said intermediate position and to resist the movement of the table into said other operative position. 105

28. A molding machine having, in combination with a table swingable from a normal operative position into a forward inverted position, of mold supporting means positioned below the table when in its inverted position and comprising a stationary supporting member, a cross bar pivoted upon said member to swing on a horizontal 110 axis extending longitudinally of the machine and substantially centrally thereof, and a pair of supporting members carried by the opposite ends of said cross bar and mounted for pivotal movement on horizontal axes extending transversely of the machine. 115

29. A molding machine having, in combination with a table swingable from a nor-

mal operative position into a forward inverted position, of mold supporting means positioned below the table when in its inverted position and comprising a stationary 5 supporting member, a cross bar pivoted on said member to swing on a horizontal axis extending longitudinally of the machine and substantially centrally thereof, and a pair of supporting members carried by the

opposite ends of said cross bar and mounted for pivotal movement on horizontal axes extending transversely of the machine, said supporting members being mounted for vertical adjustment upon said cross bar.

In testimony whereof, I have hereunto affixed my signature.

GEORGE E. PICKUP.
